ABSTRACT OF THE DISCLOSURE

A telegraph apparatus (5-unit-code) for the setting of symbols which are arranged on the circumference of a type cylinder in eight symbol rows extending in an axial direction. The type cylinder is driven by successively connected planetary gears (combined planetary gear mechanism) which are rendered operable by setting members controlled by a binary code system. The combined planetary gear mechanism has a gear ratio of 1:2, or 2:1 per gear stage. Moreover, the invention concerns a coupling system for the selective engagement of cams for one-half of a revolution. The cams provide an input to the individual stages of the combined planetary gear mechanism for the setting of a type-cylinder having a plurality of symbols in an electrically operated typewriter.

CROSS-REFERENCES TO RELATED APPLICATIONS

Applicant claims priority from corresponding German applications Ser. Nos. 101,673; 101,674 and 101,675, filed on Jan. 28, 1966.

BACKGROUND OF THE INVENTION

In the utilization of high speed type cylinder printers it is necessary to keep the mass to be moved to a minimum. Also, the apparatus for setting the type cylinder must be developed in such a way that the movement necessary to set the type cylinder is as small as possible. It is also important to maximize the time available for setting the type cylinder printer and minimize the time necessary for actuating the same.

There is known in the prior art an arrangement for setting a type cylinder printer on which there is arranged on the circumference of the cylinder in an axial direction eight rows of symbols. In this arrangement, for the axial and rotary setting of the type cylinder, there is provided a two-stage combined planetary gear mechanism having a first sun gear and two planetary gear pairs which are selectively operable by connecting rods associated therewith. As compared to other known developments, there are considerable advantages obtained through such a system. For example, the combined two planetary gear mechanism controlled by the setting rods turn or slide the type cylinder directly from one printing position into the next. In contrast to this, other known printers require that the type cylinder return to its initial position prior to each new setting. Also, in this known combined planetary gear mechanism it is possible to operate with equal setting strokes.

Accordingly, it is an object of the invention to provide an improved combined planetary gear mechanism for setting the type cylinder in such a way that the mechanism is simplified and permits larger manufacturing tolerances while still insuring that the type cylinder is brought into precise printing position.

In the utilization of high speed type cylinder printers it is necessary to move the type cylinder into the printing position as quickly as possible. When a combined plane-

2

tary gear mechanism is utilized for setting the type cylinder, it is not possible to utilize the binary code setting signals directly for shifting the type cylinder since the energy level of the signal is too low. Therefore, it is desirable to employ an auxiliary drive for shifting the type cylinder, which is energized by the setting signal.

Moreover, it is necessary in obtaining high speed operation that the type cylinder not have to be returned to a rest position after each printing, as this results in a loss of time. It is preferred that the type cylinder be moved directly from one position to the next without a return to a rest position.

There is known in the prior art an apparatus which employs a two-stage combined planetary gear mechanism for the axial and rotary setting of the type cylinder. The combined planetary gear mechanism includes a first sun wheel and two planetary gear pairs which are selectively operable by connecting rods associated therewith. In this arrangement, one of the two connecting rods, operating in an opposite sense from the other and selectable among the connecting rods, is positioned in the area of an extension which can be turned around a fixed axis through a control cam in such a way that the first sun gear and the two planetary gear pairs of the combined planetary gear mechanism are operable by the movement of the extension. This arrangement guarantees a fast operation of the setting system with a low amount of power. The position of the individual connecting rods and the individual stages of the two stage combined planetary gear mechanism remain stationary until a different position is required for the printing of the next symbol.

Another possibility exists for operating the individual stages of a combined planetary gear mechanism utilized for setting a type cylinder. In this case, the setting signal is communicated to the combined planetary gear mechanism by an auxiliary drive which utilizes eccentric cams. Each of the eccentric cams is rigidly connected to a gear which meshes with a further gear which is positioned rotatably and slidably in the longitudinal direction on a shaft. This last mentioned gear has a longitudinal slot in its axial bore which upon a shifting of the gear in an axial direction can be brought into a gripping engagement with one of two wedges which is arranged on the drive shaft. This occurs only if the wedge, which is positioned in the direction in which the gear is moved, is located in alignment with the longitudinal slot. The wedges are arranged in two axial directions on the drive shaft, i.e., they are transposed by 180°. The axial movement of the gear is effected by one of two electromagnets, and the return of the gear is accomplished by springs.

The advantage of the last mentioned arrangement for shifting the type cylinder is that the operation of the individual stages of the combined planetary gear mechanism is carried out directly through the eccentric cams. However, this advantage is considerably weakened by the fact that the control of the eccentric cams is costly, and, moreover, requires high shifting energy in order to move the gear in both directions.

Accordingly, it is a further object of the invention to provide an improved arrangement of eccentric cams for operating a combined planetary gear mechanism of a print setting apparatus.

Another problem of the prior art is the inadvertent errors and inaccuracies which occur in the manufacture of the eccentric cams. In such case, if the eccentricity is not precisely correct, the input to the gear stages of the combined planetary gear mechanism is directly affected. Correction of the eccentricity of the eccentric cams can only be accomplished by very expensive adjustment, if the previously known methods are employed.

Accordingly, it is another object of the invention to provide an improved mechanism for adjusting the input

to a combined planetary gear mechanism utilized in setting a type cylinder wherein the individual stages of the planetary gear mechanism are operated by eccentric cams which are subject to variance in manufacture.

SUMMARY

The invention relates to an apparatus for setting symbols which are arranged circumferentially on a type cylinder in eight symbol rows extending in an axial direction. The apparatus includes a combined planetary gear mechanism which, depending on the input thereto, is effective to position the type cylinder. The combined planetary gear mechanism includes a first sun gear which is driven in the first stage of the planetary gear mechanism and at the same time forms the driving gear for the second stage of the combined planetary gear mechanism.

Since one of the two sun gears is mounted between the two stages of the combined planetary gear mechanism, the mass to be moved during a cycle is decreased. This also results in the special advantage of being able to mount the bushings for the planetary gears directly on the non-rotating principle axis of the planetary gears.

In the instant combined planetary gear mechanism, the gear ratio of the first stage from the first sun gear over the planetary gear pair to the second sun gear is $3:1 \times 2:3 = 2:1$; and the gear ratio of the second stage from the aforementioned second sun gear to the power take-off sun gear over the intermediately positioned planetary gear pair is $2:1 \times 1:1 = 2:1$. In this manner, the sun gear positioned between the two stages of the combined planetary gear mechanism is utilized twice without the need for excessively increasing the planetary gears to achieve the gear ratio of 2:1 per gear stage.

According to a further improvement of the invention, the coupling system includes a plurality of eccentric cams which are positioned freely rotatably on a driving shaft. The shaft is provided with a vertically oriented, elongated slot for receiving a slidably wedge. The wedge is effective to rotate the cam when the wedge is engaged in a complementary groove provided interiorly and axially on the cam. On both sides of the wedge there are arranged resilient elements which influence the wedge selectively in one of two directions, in one of which the wedge can enter the groove in the cam and in the other of which it cannot. The movement of the wedge takes place during a short pause of the drive shaft, which is provided for by a three wheel eccentric mechanism connected between the drive motor and the drive shaft. The above described arrangement has the advantage of reducing the energy which must be expended for coupling the cams. This was one of the disadvantages of the shiftable gear arrangement which was known in the prior art, and is described hereinabove.

In a preferred arrangement of the coupling system according to the invention, the resilient elements for setting the wedge are oppositely acting spring elements arranged one on each side of the wedge for urging the wedge in either of two directions. The spring elements are intermittently spread apart by a two part cam which is mounted on the drive shaft. While the spring elements are spread apart, a setting mechanism is actuated which selectively restrains one of the spring elements and permits the other spring element to engage and move the wedge. It is also desirable that the wedge and the eccentric cam be precisely positioned during the setting operation by a locating device of some sort to insure proper alignment.

In accordance with a further improvement of the invention, three connecting rods are provided, a first of which is mounted between a first eccentric cam to a first sun gear, a second of which is mounted between a second eccentric cam and a first pair of planetary gears, and the third of which is mounted between a third eccentric cam and a second pair of planetary gears of the combined planetary gear mechanism. The connecting rods, which are driven by the eccentric cams, are attached by eccentrically positioned bolts to their respective sun gear and

planetary gear pairs so that they may be readily adjusted without requiring the variance of the eccentricity of the cams themselves.

By simply turning the eccentrically positioned bolts, the angle of the connecting rod to its respective connection in the combined planetary gear mechanism can be varied, thus, greatly reducing the manufacturing tolerances which are required of the eccentric cams.

DRAWINGS

Other objects, other advantages and aspects of the invention will become apparent by reference to the following detailed description and drawings of a specific embodiment thereof wherein:

FIG. 1 is a schematic view embodying the principles of the invention and showing the driving apparatus of a type cylinder printer for use, for example, in the telegraph art;

FIG. 2 is a front view of a two stage combined planetary gear mechanism for driving a type cylinder, removed from the remainder of the apparatus shown in FIG. 1;

FIG. 3 is an exploded schematic view of the individual parts of a sleeve bushing for supporting a planetary gear pair, and the associated forked member for connecting the bushing to its respective gear cage;

FIG. 4 shows a side elevational view taken along line 4—4 of FIG. 1, with portions removed, of an individual stage of the combined planetary gear mechanism with its respective coupling members;

FIG. 5 is an exploded schematic view of the mechanism shown in FIG. 4; and

FIG. 6 is an exploded schematic view of the eccentric attachment for securing a connecting rod to its respective gear cage.

DETAILED DESCRIPTION OF THE INVENTION

The drive mechanism shown in FIG. 1 serves to shift in an axial manner a type cylinder (not shown) of a telegraph apparatus, for example. The rotational shifting of the type cylinder can be carried out with another setting mechanism of the same type. The output of the mechanism is indicated by the arrow A, and should be connected through appropriate gears if axial movement, as opposed to rotative movement, is desired.

The drive of the entire setting apparatus is controlled by a shaft 1, (FIG. 1) labeled INPUT, which rotates with a constant speed in the direction indicated by arrow B. The input shaft 1 is connected through a three gear eccentric mechanism 2 to a drive shaft 3. With a constant and equal rotational speed applied to the shaft 1, the three gear eccentric mechanism 2 causes the shaft 3 to rotate in the same direction as shaft 1, as indicated by arrow C. The rotational speed of shaft 3 changes each cycle from zero to a maximum and then to zero again.

A trio of eccentric cams 4', 4" and 4''' are rotatably positioned on the shaft 3. During the idle phase of the shaft 3, the cams 4', 4" and 4''' may be coupled therewith for a half of a revolution depending on the position of a trio of setting elements, 5', 5" and 5'''. In other words, the particular setting of the setting elements 5', 5" and 5''' determines whether or not their respective cams are coupled to the shaft 3 during the idle phase. The setting elements 5', 5" and 5''' have a rocking motion applied thereto by the magnets 44 to move the setting elements into one of two positions. The three eccentric cams 4', 4" and 4''' are effective to drive the individual stages of the combined planetary gear mechanism through their respective connecting rods 6', 6" and 6'''. The first eccentric cam 4' acts through its associated connecting rod 6' on a first sun gear 7 of the combined planetary gear mechanism. The second eccentric cam 4" acts through its associated connecting rod 6" on a pair of planetary gears 8 and 9 which are positioned in a cage 14 and which orbit around the first sun gear 72 and a second sun gear 12, respectively. The third eccentric cam 4''' acts through its associated connecting rod 6''' on a sec-

ond pair of planetary gears 10 and 11 which are positioned in a cage 15 and which orbit around the second sun gear 12 and a third sun gear 13, respectively. The actual driving of the type cylinder (not shown), which is connected to an output shaft 42, is effected by means of a gear 16 which meshes with the third sun gear 13 of the combined planetary gear mechanism.

FIG. 2 shows the two stage combined planetary gear mechanism which is effective through the third sun gear 13 and the gear 16 to position the output shaft of 42 to which is connected a type cylinder (not shown). The three sun gears 7, 12 and 13, as well as the two planetary gear cages 14 and 15, which position the two planetary gear pairs 8-9 and 10-11, respectively, are mounted for free turning movement on a shaft 17. The connecting rod 6' is connected through a link 18 to the first sun gear 7. The connecting rod 6'' is secured to the cage 14, and the third connecting rod 6''' is secured to the cage 15. The gear ratio from the first sun gear 7 to the planetary gear 8 is 3:1; and the gear ratio from the planetary gear 9, which is rigidly connected to the planetary gear 8, to the sun gear 12 is 2:3. Therefore, the gear ratio from the sun gear 7 to the sun gear 12 is 2:1. The gear ratio from the sun gear 12, which meshes with the planetary gear 9 as well as with the planetary gear 10, to the planetary gear 10 is 2:1; and the gear ratio from the planetary gear 11 to the sun gear 13 is 1:1. Therefore, a total gear ratio of 4:2:1 results.

The planetary gear pairs 8-9 and 10-11 are positioned in sleeve bushings 19-20 and 21-22 in cages 14 and 15, respectively. The bushings 20 and 22 are pressed firmly into the cages 14 and 15, respectively, while the bushings 19 and 21 are held by forked members 23 and 24, respectively, in the cages 14 and 15. The bushings 19 and 21 must be removable in order to enable the insertion of the planetary gear pairs 8-9 and 10-11 into their respective cages 14 and 15.

FIG. 3 shows a portion of the cage 15 with the bushing 21 and the forked member 24. In the assembled condition, the forked member 24 extends into a pair of notches 25 in the bushing 21; and the bore 26 of the forked member 24 is mounted on the shaft 17.

The setting movement of the letter-digit commutation may be controlled by a 5-unit-code telegraph apparatus which is known in the art. If a 6-unit-code is employed the letter-digit commutation is carried out by the sixth code step.

The coupling apparatus which is required once for each setting cycle of the type cylinder is shown in FIG. 4 in a side elevational view. There is also shown in FIG. 4 the eccentric cam 4''' with its associated connecting rod 6''' which is secured to the cage 15. The cage 15 in turn orbits the planetary gear pair 10-11 depending on the input which is applied via the connecting rod.

The arrangement of FIG. 4 is shown in FIG. 5 in an exploded view. The shaft 3 is provided with an elongated slot 41, one for each of the three eccentric cams and the associated connecting rods. A wedge 28 is slidably mounted in each of the slots 41. The length of the wedge 28 (without the recessed portion) corresponds to the diameter of the shaft 3. The eccentric cam 4''' which is to be coupled to its associated connecting rod is loosely positioned on the shaft 3 and extends halfway across the slot 41 and the wedge 28. A coupling connection exists between the shaft 3 and the eccentric cam 4''' if the wedge 28 extends into a complementary longitudinal groove 29 which is provided in the axial bore of the eccentric cam 4'''.

When the shaft 3 is in its idle condition, a spring biased roller 30 extends into one of two notches 31 arranged in opposite sides of each of the eccentric cams 4 thereby accurately locating the cams in the idle position. A locating device 45 can be used to position the wedge 28 in the idle position.

A two-part cam 32 is mounted on the shaft 3, there being one such cam 32 for each of the eccentric cams 75

4', 4'' and 4'''.

The two-part cam 32 is coupled to the shaft 3 by a groove 33 which receives the wedge 28 mounted in the slot 41. By means of this two-part cam 32, the two legs of a V-shaped leaf spring 34 are spread apart on each operational cycle and are then released after each half-revolution of the shaft 3. In the operational area of the ends of the leaf spring 34, there is positioned a crescent-shaped attachment 35 of the respective setting member 5'''.

The setting members 5 are designed as the armature of a magnet and are shiftable by energization of magnets 44 against the influence of a spring (not shown). The upper and lower ends of the crescent-shaped attachment 35 of the setting member 5''' are effective to restrain the upper and the lower legs of the leaf spring 34, respectively, depending on the position of the setting member. In FIG. 4 the setting member 5''' is forward (to the right) and the upper end of the leaf spring 34 is restrained; the lower end is effective to urge the wedge 28 upwards. In the rearward position (to the left) the lower end of the leaf spring 34 is restrained and the upper end urges the wedge 28 downwardly. The position of the setting members 5 is determined by the signals which are sent to the magnets 44. The leg of the leaf spring 34 which is not restrained is effective to act on the wedge 28 and shift the same, if a shifting into the desired direction is possible and if the wedge is not already in the desired position through a prior setting. If, after the desired shifting of the wedge 28, the wedge 28 extends into the groove 29 of the eccentric cam 4 a coupling connection is established between the drive shaft 3 and the eccentric cam 4 for one-half of a revolution. If the groove 29 of the eccentric cam 4 is not aligned with the shifted wedge 28, then the wedge 28 only supports itself at the interior wall of the axial bore of the eccentric cam 4 and no coupling connection results between the shaft 3 and the eccentric cam 4.

The motion of the setting member 5 must occur when the two legs of the leaf spring 34 are spread apart. In the example described above, this is not the case in the idle position, so that the motion of the setting member 5 must occur prior to the reaching of the idle position. This means that the evaluation of a symbol of a binary code extends over the time period of about 1½ symbol length. As long as a plurality of symbols is evaluated in quick succession, this is of no disadvantage. In such a case, the motion of the setting members 5 can take place during the evaluation of the preceding symbol. As a rule, only individual symbols, or individual small groups of symbols, are evaluated, and the apparatus is stopped by a special circuit coupling during the pauses. In such a case, it is advantageous to supplement the above described coupling system with an additional mechanism.

As is shown in FIG. 5, this supplemental mechanism consists of a disc 36 which is rotatably positioned on the shaft 3 in the area of the cam 32. The disc 36 is provided with two extensions 37 and an actuation lever 38. In the idle position, the extensions 37 of the disc 36 are turned in such a manner that the ends of the leaf spring 34, which are spread apart by the two-part cam disc 32, support themselves on the extensions 37. Thus, the motion of the setting member 5 can take place in this position. Shortly before the rotation of the shaft 3, the disc 36 is rotated by the actuation lever 38 so that the extensions 37 release the ends of the leaf spring 34 and the desired movement of the wedge 28 can take place.

A coupling connection results in the above described coupling system only when the next following setting criteria deviates from the preceding setting criteria. This is so since the groove 29 in the eccentric cam 4 is located in a position, after the advancement of the shaft 3 according to one criterion, which is different from the setting position caused by a similar setting criterion. Thus a coupling connection can no longer take place.

FIG. 6 shows a portion of the cage 15 and additionally

discloses an attachment screw 39 which fits in a bore 27 in the planetary gear cage 15. The screw 39 is threaded into an eccentric bore of a bolt 40 for affixing the connecting rod 6 to the cage 15. By turning the bolt 40 on the threaded screw 39, the setting angle between the connecting rod and the cage 15 can be changed. The connection of a similar eccentrically bored bolt to the link 18 of the first sun gear and another to the planetary gear cage 14 permits similar adjustment of the other connecting rods.

It has been found that an eccentric positioning of the bolts 40 by 0.15 mm. at a turning radius at about 12 mm. and a normal shifting angle of 45° results in a change of this shifting angle by over 1°.

The above described coupling system according to the invention is very simple in its construction and mode of operation. Moreover, a very low control power is necessary to operate the coupling system. In addition, only two control positions are required.

Preferably, a two-legged leaf spring 34 is employed for each coupling unit to shift its associated wedge. The operational ends of the leaf springs, which are either acting on the wedge 28 or are restrained by the crescent shaped member 35 of the setting member 5, are directed in the same direction of rotation in relation to the drive axis, preferably, in the direction of rotation of the drive shaft. This is advantageous since the setting paths of the setting elements can thereby be kept to a minimum.

The above described improved coupling system according to the invention is advantageous if a plurality of symbols are to be printed in quick succession, since the setting criteria for the printing of a symbol must be rendered effective no later than after one-half of the previous operational cycle. This takes place during the printing of the previous symbol, and thus no loss of time occurs.

If only individual symbols or symbol groups are usually printed, then it is advantageous to employ between the motor (not shown) and the three gear eccentric mechanism 2, or even instead of the three gear eccentric mechanism 2, an ordinary electromagnetically controlled circuit coupler. Such a coupler would hold the drive shaft of the couplings for one-half of a revolution per symbol, thus stopping the apparatus in the operational phases. However, it is then desirable to utilize a supplemental system, described above as disc 36, which is characterized by the fact that it has extensions 37 which act as supporting members for the spring elements 34 in the idle position of the shaft. After the completed setting of the setting elements and prior to the beginning of the rotary movement of the drive shaft 3, the leaf spring 34 is released by turning the disc 36 and its associated extensions 37. The rotation of the actuation levers can suitably be accomplished by the use of magnets.

In addition to the above-described utilization of the instant apparatus, the eccentric cam of the coupling system according to the invention can for example, also be employed for lifting, lowering and advancing a type cylinder and for the line advancement.

What is claimed:

1. An apparatus for setting symbols which are arranged on the circumference of a type cylinder in eight axial rows, which comprises:

a two stage combined planetary gear mechanism for driving the type cylinder, which includes:

first (7), second (12) and third (13) sun gears;

a first pair of integrally associated planetary gears (8, 9), one of which (8) is in mesh with the first sun gear (7) and the second (9) of which is in mesh with the second sun gear (12);

a second pair of integrally associated planetary gears (10, 11), one of which (10) is in mesh with the second sun gear (12) and the other of which (11) is in mesh with the third sun gear (13) so that the driven sun gear (12) of the first stage of the com-

bined planetary gear mechanism forms the drive for the sun gear (13) of the second stage of the mechanism, said gear stages having a gear ratio of 1:2 or 2:1 per gear stage;

first (6'), second (6'') and third (6''') input connecting members, said first input member (6') being directly connected with the first sun gear (7), and the second and third input connecting members being connected to the first pair of planetary gears (8, 9) and the second pair of planetary gears (10, 11), respectively, for selectively supplying input rotation to the gears of the combined planetary gear mechanism; and

means (4', 4'', 4'''), etc.) for selectively actuating the connecting members (6', 6'', 6''') to vary the output of the combined planetary gear mechanism and properly position the type cylinder for the printing of the next symbol.

2. Apparatus as recited in claim 1 wherein the gear ratios in the first gear stage including the first sun wheel (7), the first planetary gear pair (8, 9), and the second sun gear (12) are $3:1 \times 2:3 = 2:1$, and the gear ratios in the second gear stage including the second sun gear (12), the second planetary gear pair (10, 11) and the third sun gear (13) are $2:1 \times 1:1 = 2:1$.

3. Apparatus as recited in claim 1 which further includes:

sleeve bushings (19, 20 and 21, 22) for supporting the planetary gear pairs (8, 9 and 10, 11) in their respective cages; and

forked members (24) for engaging the bushings and releasably attaching one end of each of the planetary gear pairs to its respective cage.

4. Apparatus as recited in claim 1 wherein said actuating means comprises:

a drive shaft (3) having a longitudinally extending slot (41) which is perpendicular to the axis of rotation of the shaft;

means (1, 2) for applying intermittent rotation to the shaft (3),

a coupling apparatus for selectively conveying the intermittent rotative motion from the shaft (3), to the connecting members which includes:

a cam (4) mounted freely on the shaft (3) for selectively receiving rotative motion therefrom, said cam having a longitudinal groove (29) in the axial bore thereof, and said cam being effective to convey motion to the connecting members;

a wedge (28) slidably positioned in the slot (41), said wedge being receivable in the longitudinal groove (29); and

means for shifting said wedge (28) in the slot (41) into one of two positions, wherein in one of the positions the wedge (28) is in the groove (29) and communicates the rotation of the drive shaft (3) to the cam (4) and in the other position the wedge (28) is not in the groove (29) and the cam (4) is disengaged from the drive shaft (3).

5. Apparatus as recited in claim 4 wherein said shifting means includes:

a pair of spaced spring elements (34), one positioned on either side of the wedge (28), said spring elements acting in opposite directions on the wedge for urging the wedge in either one of the two positions;

a cam (32) mounted on the drive shaft (3) for cyclically spreading the spring elements (34) away from the wedge (28);

setting means (5), operable while the spring elements are spread away from the wedge, for selectively positioning the wedge, said setting means having two operating positions, in one of which a first of the spring elements is restrained while the second spring element acts on the wedge, and in the other operating position the second spring element is restrained while the first spring element acts on the wedge.

6. Apparatus as recited in claim 5 which further comprises:

an actuation lever (38) having two extensions (37) for supporting the spring elements (34) in the spread apart position while the drive shaft (3) is in the idle condition, said lever being rotatable after the actuation of the setting member (5) and prior to the next rotation of the drive shaft (3) to release the spring elements (34).

7. In combination with an apparatus for setting symbols which are arranged on a type cylinder, said cylinder being drivable by a combined planetary gear mechanism having inputs from a plurality of cams, the improvement which comprises:

a drive shaft (3) having a longitudinally extending slot (41) which is perpendicular to the axis of rotation of the shaft;

means (1, 2) for applying intermittent rotation to the shaft (3),

a coupling apparatus for selectively conveying the intermittent rotative motion from the shaft (3), to the connecting members which includes:

a cam (4) mounted freely on the shaft (3) for selectively receiving rotative motion therefrom, said cam having a longitudinal groove (29) in the axial bore thereof, and said cam being effective to convey motion to the connecting members;

a wedge (28) slidably positioned in the slot (41), said wedge being receivable in the longitudinal groove (29); and

means for shifting said wedge (28) in the slot (41) into one of two positions, wherein in one of the positions the wedge (28) is in the groove (29) and communicates the rotation of the drive shaft (3) to the cam (4) and in the other position the wedge (28) is not in the groove (29) and the cam (4) is disengaged from the drive shaft (3).

8. Apparatus as recited in claim 7 wherein said shifting means includes:

a pair of spaced spring elements (34), one positioned on either side of the wedge (28), said spring elements acting in opposite directions on the wedge for urging the wedge in either one of the two positions;

a cam (32) mounted on the drive shaft (3) for cyclically spreading the spring elements (34) away from the wedge (28);

setting means (5), operable while the spring elements are spread away from the wedge, for selectively positioning the wedge, said setting means having two operating positions, in one of which a first of the spring elements is restrained while the second spring element acts on the wedge, and in the other operating position the second spring element is restrained while the first spring element acts on the wedge.

9. Apparatus as recited in claim 8 which further comprises:

5 an actuation lever (38) having two extensions (37) for supporting the spring elements (34) in the spread apart position while the drive shaft (3) is in the idle condition, said lever being rotatable after the actuation of the setting member (5) and prior to the next rotation of the drive shaft (3) to release the spring elements (34).

10. Apparatus as recited in claim 8 which further comprises a positioning device (45) for locating the wedge (28) after each cycle.

11. Apparatus as recited in claim 8 wherein said cam (4) has a pair of opposed notches (31) in the periphery thereof; and which further includes:

a spring biased roller (30) receivable alternately in the notches for positioning the cam after each cycle (one half revolution).

12. Apparatus as recited in claim 7 wherein said cam (4) is connected to said combined planetary gear mechanism by a rod (6) which communicates the rotative motion of the cam to the combined planetary gear mechanism, and which further comprises:

an eccentrically and interiorly thread bolt (40) on which is mounted the output end of the rod (6); and and exteriorly threaded screw (39) for connecting the bolt (40) to the combined planetary gear mechanism,

whereby the angle of the rod (6) can be varied with respect to the combined planetary gear mechanism by turning the bolt (40).

13. In combination with a 5-unit code telegraph apparatus for setting symbols which are arranged on the circumference of a type cylinder in eight axial rows, under the control of a successively switched two stage combined planetary gear path mechanism having a gear ratio of 1:2 or 2:1 per stage and settable by actuating means through binary code combination steps corresponding to the code-combination digit or letter change, the sun gear of the first stage and the two planetary gear pairs of the two stages being actuatable by connecting rods into two positions each, wherein the improvement comprises:

45 said driven sun gear of the first stage of the combined planetary gear path mechanism forms the driving sun gear of the second stage of the combined planetary gear path mechanism.
